PRODUCTION OF DIOLEFINS

Frederick E. Frey, Bartlesville, Okla., assignor to
 Phillips Petroleum Company, a corporation of
 Delaware

Application August 30, 1940, Serial No. 354,890

6 Claims. (Cl. 260—681.5)

This invention relates to the production of diolefin hydrocarbons from paraffin hydrocarbons by dehydrogenation. It relates more particularly to the production of such diolefins by the use of a single dehydrogenation step. The invention has particular reference to the production of diolefins such as butadiene, pentadiene, and isoprene from the corresponding paraffin hydrocarbons.

An appreciable number of diolefins such as those just mentioned have been known to the art for a number of years. These have been produced in a number of ways which have included cracking of heavier oils, the copolymerization of acetylene and ethylene to form butadiene, catalytic or thermal conversion of alcohols, both of the same number of carbon atoms per molecule as the desired diolefin and of a fewer number of carbon atoms per molecule, and other more or less involved chemical processes, as well as the dehydrogenation of the corresponding olefins which in turn may have been produced by the dehydrogenation of the corresponding paraffins. This latter procedure, although it appears to be one of the more direct methods for the production of diolefins, has not as yet found very extensive commercial application, and involves a somewhat complicated procedure including dehydrogenation to form olefins, separation of olefins in a more or less concentrated form, dehydrogenation of these olefins to form diolefins, and separation of a diolefin so produced from unreacted olefins. However, direct as this process appears to be, most of the commercial installations to date have been one of the former types rather than a process involving only direct treatment of hydrocarbons of the same number of carbon atoms per molecule.

I have now found that I can successfully produce substantial yields of diolefins from the corresponding paraffins by a process which involves a single dehydrogenation step. In a simple modification my invention comprises passing a paraffin hydrocarbon to a dehydrogenation step which is adapted to effect a production of diolefins, separating most or all of the hydrogen and any light hydrocarbons from the effluent, separating and recovering the desired diolefins so produced, and returning to the dehydrogenation a hydrocarbon material comprising unreacted paraffins together with the corresponding olefins which have been produced in the dehydrogenation. This dehydrogenation step apparently does not form the major part of the diolefin product by a dehydrogenation of a paraffin directly to a diolefin with no intermediate reactions, but apparently cooperates with the rest of my process to effect a dehydrogenation of paraffins to olefins and concomitantly a dehydrogenation of olefins to diolefins, the latter being produced in substan-

tial quantities. However, in any clean cut dehydrogenation process the initial products, once formed, tend to reunite by the reverse reaction of hydrogenation, so that the concentration of dehydrogenation products approaches only an equilibrium value, dependent on the various reaction conditions present. For these reasons, the maximum value of the diolefin concentration, although substantial, will be low.

My invention further comprises various preferred methods of separating the dehydrogenation effluent into the desired constituents.

It is an object of my invention to produce diolefin hydrocarbons from paraffin hydrocarbons of the same number of carbon atoms per molecule.

Another object of my invention is to produce from paraffin hydrocarbons diolefin hydrocarbons in a process which involves a single dehydrogenation step.

A further object of this invention is to separate diolefin hydrocarbons from the effluent of a dehydrogenation wherein olefins and diolefins, together with free hydrogen, are produced from paraffin hydrocarbons.

It is another object of this invention to produce diolefin hydrocarbons from the corresponding paraffin hydrocarbons of the same number of carbon atoms per molecule.

Further objects and advantages of this invention will become apparent from the accompanying disclosure and discussion.

In a preferred form of my invention I employ a dehydrogenation catalyst to effect a production of diolefins. In order to obtain the best yields of diolefins from my process, and to operate it most successfully, I find it necessary to employ only the more efficient dehydrogenation catalysts, and to employ dehydrogenation conditions at which there is only a minimum of scission of carbon to carbon bonds. In this manner I am able to obtain high yields of diolefins of the same number of carbon atoms per molecule as the original paraffins, and also with the corresponding arrangement of carbon atoms. Furthermore, since my invention involves the production and treatment of olefin hydrocarbons corresponding to the desired diolefins, I am able to include in my process relatively simple separation equipment for the recovery of the diolefins, the elimination of low boiling dehydrogenation products, and the separation of a recycle fraction composed of paraffins and olefins. Any dehydrogenation catalyst with the foregoing characteristics is suitable for use in my process. However, I have found that the most desirable catalysts for my process are those that consist of or comprise chromium oxide, and especially unglowed chromium oxide or chromium oxide gel, which is generally dark, or black, such as was first described by Huppke and Frey

in U. S. Patent 1,905,383, or a modified form of this material as disclosed by Frey and Huppke in U. S. Patent 2,098,959, and is also disclosed in various copending applications which include Morey, Serial No. 113,091; Matuszak and Morey, Serial No. 173,708 (Patent No. 2,294,414); Morey and Frey, Serial No. 173,709 (Patent No. 2,312,572); Morey and Frey, Serial No. 359,296, filed October 1, 1940, and others. The dehydrogenation pressure should not be very high, that is, generally it should not exceed 50 or 100 pounds per square inch gauge, and in most instances should be only slightly above atmospheric. At times a subatmospheric pressure may be used, but although a low pressure favors the dehydrogenation reaction subatmospheric pressures will generally not be used in plant operations. A low partial pressure of the hydrocarbon material present along with a total pressure above atmospheric may be realized by dehydrogenating the hydrocarbons in admixture with an inert gas such as nitrogen or the like, as is known to the art. Although the presence of free hydrogen tends to have an adverse mass action effect, a small amount of free hydrogen in the charge stock often appears to have a beneficial effect upon the catalyst, especially on the initial portions of the catalyst with which the charge stock comes into contact. Other modifications of dehydrogenation operation known to the art may also be used. With a given dehydrogenation pressure and catalyst activity, the dehydrogenation temperature and reaction time will be interdependent and will have in general an inverse relationship. The dehydrogenation temperature will be within the range known for catalytic dehydrogenation, but preferably will not be in the upper part of the range but will be between about 700 and 1150° F. Lower temperatures, even with long reaction times, will give uneconomically low yields, and higher temperatures, even with very short reaction times, will result in excessive formation of low boiling hydrocarbon products. I prefer to operate under constant conversion conditions with gradually increasing temperatures as a particular body of catalyst becomes deactivated. With a fresh body of active catalyst, which will produce satisfactory dehydrogenation at a relatively low temperature, a flow rate adapted to give dehydrogenation not far short of equilibrium, may be used. If this flow rate is maintained as the temperature is increased, to provide for a relatively constant extent of conversion as the catalyst becomes less active, the reaction conditions will generally be such at the higher temperatures that excessive deleterious secondary or side reactions are not encountered.

The paraffin hydrocarbons charged to my process should be in a more or less pure state when it is desired to produce substantially pure di-olefins. My process is particularly adapted to the production of butadiene, normal pentadiene, and isoprene from normal butane, normal pentane, and isopentane respectively. These paraffin hydrocarbons may be considered as members of the group of paraffins of not more than five carbon atoms per molecule and of the type

wherein each R is one of the group consisting of hydrogen and methyl. Each of the hydrocarbons of this group can be readily isolated in a state of purity, from any natural occurring or other suitable source of hydrocarbons which contains

them, by simple fractional distillation and each adapted to efficient nondestructive dehydrogenation under the conditions disclosed herein. While individual hydrocarbons of a purity greater than 99 per cent may be obtained by fractional distillation, such purity is often quite expensive to obtain and is generally not necessary for the ordinary commercial application of my invention. The recycle feature of my process tends to build up undesirably high concentrations of isomers of the hydrocarbons which are being treated by my invention, and the charge stock should be sufficiently pure that this effect is not too predominant. This effect is also readily controlled by periodic or continuous removal and refractionation of a portion of the recycled hydrocarbon material, as will be discussed. For most uses of my invention the charge stock will preferably consist of a hydrocarbon material of a given carbon skeleton structure in a concentration of at least about 95 per cent of the hydrocarbons present. Although the invention applies primarily to a paraffinic charge stock direct from some natural source, if a hydrocarbon fraction is available which contains olefins of the same carbon skeleton structure as the paraffins and substantially free of isomeric paraffins and/or olefins, it will also be a material suitable for charging to my process, and a hydrocarbon material of a given carbon skeleton structure will be understood to include such olefins as well as the paraffins.

My invention will now be more specifically described in connection with the accompanying drawings, which show diagrammatically by way of flow sheets two modifications of apparatus for practicing my invention.

Figure 1 illustrates an arrangement of apparatus wherein the diolefin product is recovered by means of a selective absorbent for unsaturated hydrocarbons.

Figure 2 illustrates an arrangement of apparatus wherein the diolefin product is recovered by means of an absorbing medium which selectively enters into combination with a diolefin to form a readily separated and decomposable product.

Referring now to Figure 1, a paraffin hydrocarbon material of four or five carbon atoms per molecule, which may be essentially normal butane, normal pentane, or isopentane as discussed, enters the system through pipe 10 and is passed at a relatively low pressure to dehydrogenation unit 11. The dehydrogenation unit 11 is comprised of suitable heating units or furnaces, catalyst chambers, and the like known to the art for effecting and maintaining catalytic nondestructive dehydrogenation of low boiling hydrocarbons.

The catalyst chambers may be so arranged that heat is supplied to the catalyst body, or bodies, and the reacting mixture. However, when a steady state of operation is reached only a limited amount of dehydrogenation actually takes place per pass, since the net amount will be the dehydrogenation of a small amount of butane to form butenes and of butenes to form a corresponding amount of butadiene, when the process is operated to produce butadiene, and a large substantially adiabatic catalyst chamber may be used with an adequate heating of the stream charged to such chamber. The hydrocarbons charged to the process are joined by recycled paraffins, and olefins of a like number of carbon atoms per molecule previously produced in the dehydrogenation unit, passing through pipe 32.

The dehydrogenation is conducted to effect a dehydrogenation both of paraffins and olefins to form olefins and diolefins, respectively, along with free hydrogen. The resulting products pass through pipe 12 and valve 13 to the absorber 14, entering at a low point. Absorber 14 is provided with suitable bubble trays, or packing, or the like, not shown, known to the art and suitable for effecting intimate contact between an ascending fluid and an immiscible descending liquid. The ascending fluid will be either liquid or gaseous, generally gaseous, comprising free hydrogen and paraffin and olefin hydrocarbons of the dehydrogenation effluent, and the descending liquid will comprise a suitable absorbent liquid introduced near the top of the absorber, together with absorbed diolefin hydrocarbons. The dehydrogenation effluent will be suitably cooled before entering absorber 14, as by means of a cooler incorporated as a part of the dehydrogenation unit, or in pipe 12, not shown. The absorption liquid will be likewise suitably cooled, by means not shown, such as a cooler in pipe 51.

A trap-out tray 15 is provided near the bottom of the absorber, preferably below the inlet pipe 12. The rich absorbent liquid, which will contain some olefins as well as the desired diolefins, is removed from the trap-out tray 15 through pipe 16, and is passed by suitable means through heating coil 17 and pipe 18 to a reboiler 20 which comprises the bottom of absorber 14. Vapors released from the rich absorption liquid by this treatment, which will contain a higher ratio of olefins to diolefins than is present in the absorbed material contained in the liquid passing through pipe 16, pass up through the trap-out tray 15 to meet the descending absorption liquid.

Unabsorbed material, which comprises essentially free hydrogen, unreacted paraffins, and olefins of the same number of carbon atoms per molecule produce by the dehydrogenation, together with possible small amounts of lower boiling hydrocarbons, pass from a high point of absorber 14 through pipe 23 and valve 24, is suitably compressed by compressor or pump 25, and passed through pipe 26 to separating means 27. A suitable cooling means, not shown, may be inserted in pipe 26 or incorporated as a part of the separating means 27. The separating means is adapted to effect a separation between a hydrocarbon material comprising essentially paraffins and olefins which are to be recycled to the dehydrogenation step, and a lower boiling material comprising essentially free hydrogen, which is removed from the process through pipe 30 and valve 31. The recycle stock is withdrawn through pipe 32 and passed through valve 33 to pipe 10 to be mixed with a paraffin hydrocarbon material charged to the process. If desired, a part or all of the stream may be used to effect a part of the cooling required in connection with separating means 27, this being accomplished by passing the liquid stream through pipe 34 and valve 35 to vaporizing or cooling coil 36, and then through pipe 37 and valve 38 back to pipe 32, with the valve 33 being partly or completely closed. Although it is primarily intended to treat a single paraffin hydrocarbon, it is generally not economical to isolate such a material in a completely pure state, though it is not too difficult or expensive to produce by fractional distillation a material which is 95 to 97 per cent pure. I have found such a charge to be of a satisfactory purity. However, impurities present in this charge tend to build up in the system, so that it is often de-

sirable to remove a portion of the recycle stock, continuously or intermittently from pipe 32 through pipe 40 and valve 41. Material so removed may be subjected to further separation, with the desired recovered hydrocarbons being reintroduced to the system with fresh paraffins through pipe 10.

The rich absorption liquid, containing desired diolefins, is removed from the reboiler 20 through pipe 42 and passes through valve 43 to the top of a first stripper 44. A portion only of the absorbed material is removed in this stripper, and will comprise a substantial portion of diolefin together with the major part of any remaining absorbed olefin. The material so removed is returned, at least in part, through pipe 45 and valve 46 to the liquid in reboiler 20. A portion of this unsaturated material may be removed from the system through pipe 47 and valve 48, if desired, for further treatment. The partially stripped rich absorbent passes from a low point of stripper 44 through pipe 50 and valve 51 to stripper 52, wherein it is completely freed of absorbed hydrocarbons. The material so removed will comprise essentially the desired diolefin and is recovered as a product of the process through pipe 53 and valve 54. As an aid to the concentration of diolefin in the original rich absorbent, and removal of undesired absorbed olefins, a portion of this diolefin material may be returned to the reboiler 20 from pipe 53 through pipe 55 and valve 56. The denuded lean absorbent liquid is removed from a low point of stripper 52 through pipe 57 and valve 58 to a high point of absorber 14. Any heavier hydrocarbons which may be formed in the dehydrogenation step in small amounts will collect in this absorption oil and build up in the system. Any such accumulation may be controlled and limited by withdrawing a portion of the lean absorption oil from the system through pipe 61 and valve 62, and removing such heavy hydrocarbons, and if desired returning the purified oil to the system by means not shown.

The procedure just described for the apparatus shown in Figure 1 is for the process which has reached a steady state of operation. In initially starting the dehydrogenation step, only a small amount of diolefin will be formed, and it will generally be desirable to recycle the entire hydrocarbon material for a short period. This can be done by use of the by-pass 21 with valve 22 open and with valve 13 partially or completely closed. At this time as well as during subsequent steady-state operation, it may be desirable to include a small amount of free hydrogen in the recycle stream passing through pipe 32, so that the initial part of the catalyst bed or beds used in the dehydrogenation unit 11 will operate in the presence of small amounts of free hydrogen, as well as subsequent portions of said beds. After the diolefin concentration of the effluent has risen to an appreciable value, such as 3 or 4 to 6 or 8 per cent, the effluent is passed to the absorber, as discussed.

The absorption liquid used in absorber 14 is one in which unsaturated hydrocarbons are preferentially dissolved and paraffin hydrocarbons are only slightly soluble. It is desirable that this absorption medium have only a limited capacity for solution even of the unsaturated hydrocarbons, otherwise the resulting solution will tend to be completely miscible with all hydrocarbons after taking up an appreciable quantity of unsaturated hydrocarbons. This can be somewhat limited and controlled by operating at a suitably low tem-

perature. Many such solvents are known to the art, and include water, furfural, various glycols and their organic esters such as the glycol acetates, glyceryl ethers, lactic acid esters, alkyl amines, and especially aqueous solutions of such materials. A suitable but somewhat different class of solvents are the SO_2 -olefin-resin oils disclosed by Snow in his Patent 2,163,588. Any such solvent or absorption liquid will tend to absorb mono-olefins as well as diolefins, a property which will tend to increase at first upon the absorption of diolefins but which I have found can be counteracted and suitably controlled by proper control of temperature and pressure of the rich absorbent, together with judicious recycling of various streams as has just been described in connection with Figure 1. The rich absorbent, containing some mono-olefins as well as the desired diolefins, which collects on tray 15, is heated and returned to reboiler 20 wherein it has added to it diolefin concentrates introduced through pipe 45 and/or pipe 55. This treatment has the effect of vaporizing absorbed mono-olefins both as a result of the heating and of the increased concentration of diolefin. Mono-olefins which remain and are present in the material passed through pipe 42 are substantially completely removed in the preliminary stripper 44.

Although some diolefin is likewise vaporized at this point, it is recovered within the system, as will be readily appreciated, and after the absorption and recovery system has reached a steady state of operation the stream passing through pipe 23 will be substantially free of diolefin and contain mono-olefin equivalent in amount to that present in the stream entering the bottom of the absorber through valve 13. Likewise, the stream recovered as a product of the process through pipe 53 and valve 54 will comprise diolefins in high concentration and in an amount equivalent to that produced by the dehydrogenation and entering the absorber through valve 13, an amount which will also be practically equivalent to the fresh hydrocarbon material of the same carbon skeleton structure charged to the process through pipe 10. If the absorbent is sufficiently selective in its action, the primary stripper 44 may be omitted, and the rich absorbent passed directly from pipe 42 through pipe 59 and valve 60 to pipe 50 and stripper 52.

Referring now to Figure 2, this shows an alternative but not completely equivalent recovery process for recovering the desired diolefin product, the dehydrogenation step being substantially the same as that just described in connection with Figure 1. A suitable hydrocarbon material enters the system through pipe 10 and is passed at a relatively low pressure to dehydrogenation unit 11, as previously discussed. The paraffins charged to the process are joined by recycled paraffins, and olefins of a like number of carbon atoms per molecule previously produced in the dehydrogenation unit, passing through pipe 32. The dehydrogenation products pass through pipe 12, compressor 125, and valve 113 to separating means illustrated by absorber 114, entering at a low point. Absorber 114 is equipped with suitable bubble trays or packing or the like, and is operated primarily to effect a separation between free hydrogen and any light gases on the one hand, and diolefins, olefins, and unreacted paraffins on the other. If a single absorber is used, as shown, this may be accomplished by passing a relatively non-selective absorption liquid to the top of the absorber, letting it pass downwardly countercurrent

to ascending gases and vapors. Free hydrogen, along with any light gases, is removed through pipe 30 and valve 31. A rich absorption liquid passes from a low point of the absorber 114 through pipe 115 and valve 116 to a high point of stripper 117. The absorbed hydrocarbons are removed from the absorption liquid, and this latter passes in a lean state from a low point of stripper 117 through pipe 118 and valve 119 to the top of absorber 114.

Any heavier hydrocarbons which may be formed in the dehydrogenation step in small amounts will collect in this absorption oil and build up in the system. Any such accumulation may be controlled and limited by withdrawing a portion of the lean absorption oil from the system through pipe 126 and valve 127, and removing such heavier hydrocarbons, and if desired returning the purified oil to the system by means not shown.

The hydrocarbon material so removed, which comprises essentially paraffins, olefins, and diolefins of the same number of carbon atoms per molecule, passes through pipe 130 and valve 131 to a second separating means such as the absorber or fractionator 132. When used as an absorber, it is preferably used in conjunction with a material which reacts selectively with diolefins to form a readily decomposable chemical compound. Such materials are known to the art and include aqueous solutions or compositions of a salt of a heavy metal of groups I and II of the periodic system, especially of such a metal in monovalent form, as a cuprous halide, or a mercurous or silver salt, and especially an aqueous alkali-halide-containing solution, or suspension, of cuprous chloride. Such a material is introduced near the top of absorber 132 and is intimately mixed, as it passes downwardly, with ascending hydrocarbon material. A hydrocarbon material comprising essentially paraffins and olefins passes from the top of absorber 132 through pipe 32, and is passed through valve 33 to pipe 10, to be mixed with the hydrocarbon material charged to the process. If desired a part or all of this material may be used to effect a part of the cooling required in connection with separating means 114, especially if the material passing through pipe 32 is in the liquid state and is substantially above the pressure required in the dehydrogenation unit 11. This cooling may be carried out by passing the material through pipe 34 and valve 35 to cooling coil 36, and then through pipe 37 and valve 38 back to pipe 32 with the valve 33 being partly or completely closed. As previously mentioned in connection with Figure 1, a portion of this stream may be continuously or intermittently removed through pipe 40 and valve 41 for further separation of its components.

A solution or slurry containing the resultant diolefin complex passes from absorber 132 through pipe 133 and valve 134 to stripper 135, wherein the diolefin is separated from the complex compound, as by heating, and is recovered as a product of the process through pipe 136 and valve 137. The other component of the complex compound is recovered and returned to the absorber 132 through pipe 138 and valve 139.

This procedure is adapted to the production and separation of all low boiling diolefins which are readily produced by the catalytic dehydrogenation of paraffins and olefins. In the case of the production and recovery of pentadiene from normal pentane, the process of Figure 2 may be somewhat simplified and modified to recover the pentadiene by fewer operations. The separating

means 132 may be operated as a fractionator in this case, and the higher boiling pentadiene may be recovered by simple fractional distillation from the lower boiling normal pentane and pentenes. In such a case, the normal pentane and pentenes pass overhead through pipe 32, and pentadiene is removed from the system through pipes 133 and 142, and valve 143, valve 134 being closed. In either modification, separating means 114 may be used as a fractionator rather than an absorber, with a desired hydrocarbon material containing diolefins to be recovered passing as a kettle product directly through pipe 115 and pipe 140 and valve 141 to pipe 130 and separating means 132, valves 116 and 131 being closed.

In the modification of Figure 2 also it may be desirable at the start of a run to recycle a portion or all of the dehydrogenation effluent, or of the hydrogen-free hydrocarbon material, for a short period. Recycle of the entire effluent can be effected by use of the bypass 121 with valve 122 open and valve 113 partially or completely closed. Recycle of unseparated hydrocarbon material may be readily realized by removal of a part or all of the stream normally entering separating means 132, by means not shown, and returning it to the process through pipe 10.

As an example of the operation of one modification of my process, a butane stream comprising about 97 per cent normal butane, with the remainder primarily isobutane, may be passed at a temperature of about 950° F. over a large mass of dehydrogenation catalyst comprising a dried and reduced mixed gel of chromium oxide and alumina, prepared as described in U. S. Patent 2,098,959 to Frey and Huppke, on an inert granular support. The pressure is only sufficiently above atmospheric to provide a slight positive superatmospheric pressure through the dehydrogenation step, and the rate is about 300 gaseous volumes of total charge stock, measured at ordinary temperatures and pressures, per volume of space occupied by the catalyst per hour. As the process is initially started the effluent contains, by volume, about 15 per cent each of hydrogen and normal butenes, the remainder being primarily unreacted butane with a practically negligible quantity of butadiene. Free hydrogen is removed from this initial effluent by simple cooling and liquefaction of the C₄ hydrocarbons, with the C₄ hydrocarbon material so recovered being returned directly to the inlet of the dehydrogenation step. As the products of this first recycle portion of the continuous charge stream appear in the effluent the butadiene content of the effluent, produced by dehydrogenation of butenes, rapidly approaches a value of about 4.5 per cent, with about 65 per cent unreacted butane and about 18 per cent butenes, the remainder being essentially free hydrogen. At this stage of the operation, in addition to the removal of free hydrogen from the effluent, the effluent is also treated to remove a butadiene concentrate, as described in connection with Figure 1, using methyl lactate as the absorbent. A substantially butadiene free C₄ hydrocarbon mixture, containing a little over 20 per cent butenes, is recycled to the inlet of the dehydrogenation step, with additional normal butane being added in an amount substantially equivalent to the butadiene removed, so that the total quantity of C₄ hydrocarbon material subjected to dehydrogenation is maintained constant. As the dehydrogenation catalyst mass loses activity, the temperature of the charge is raised to a maximum of about 1050° F. at a rate

sufficient to maintain a substantially constant amount of conversion, and as the maximum temperature is reached a fresh catalyst mass, at an initial temperature again of about 950° F. is switched into operation. As the process reaches a steady state of operation the total charge, including added butane, and the effluent have approximately the following compositions, in percent by volume of the gaseous mixture.

Component	Effluent	Charge
H ₂	12	
C ₄ H ₁₀	60	75
C ₄ H ₈	22	25
C ₄ H ₆ (Butadiene)	6	
	100.0	100.0

About 2 per cent of the recycle C₄ hydrocarbon mixture is continuously discarded from the process, thereby maintaining the normal C₄ hydrocarbons in the total charge at a value greater than 95 per cent.

As previously mentioned, the dehydrogenation carried out in unit 11 is conducted under a relatively low pressure, which should not appreciably exceed about 50 or 100 pounds per square inch gauge, and which in most instances will be nearer atmospheric pressure and may even be subatmospheric. In many instances, therefore, the dehydrogenation pressure will be less than the pressure of the source of the material charged through pipe 10, and a pump or compressor will not be necessary for this stream. A compressor 25 has been shown in Figure 1, and a compressor 125 in Figure 2. For most adaptations of my invention such compression of part or all of the dehydrogenation effluent will be the only compression and pumping used on the stream which contain or comprise olefins and unreacted paraffins destined to be recycled to the dehydrogenation unit 11, a feature which is one of the advantages of my process. Although other pumps or compressors for other streams have not been shown, the general flow of the various streams is indicated and has been discussed, and suitable mechanical equipment of this nature can be readily supplied as required in any particular application of my invention by one skilled in the art. Similarly, other units of equipment have been shown only diagrammatically, but have been described and the functions explained so as to serve as suitable guides for adaptation of suitable specific equipment for specific installations. It will be obvious to those skilled in the art that various modifications of my invention may be practiced as being included in the spirit of the disclosure and in the scope of the claims.

I claim:

1. An improved process for the separation of butadiene produced by the dehydrogenation of normal C₄ hydrocarbons from accompanying dehydrogenation products, which comprises passing the effluent from such a dehydrogenation to a low point of an absorber, passing to a high point of said absorber a lean selective absorption liquid to effect a selective absorption of unsaturated hydrocarbons, removing unabsorbed gases from the absorber, passing a rich absorbent liquid stream from said absorber step to a first stripper, effecting in said first stripper a partial stripping of said rich absorbent to remove therefrom a less unsaturated hydrocarbon material and returning at least a portion of the same to a low point of said absorber, passing the resultant par-

10 tally stripped rich absorbent liquid to a second stripper, removing therefrom remaining absorbed material comprising predominantly butadiene, passing a resultant lean absorption liquid to a high point of said absorber, returning a portion of said separated absorbed butadiene material to a low point of said absorber, and removing from the process as a butadiene product a further portion of said material.

20 2. An improved process for the separation of a low-boiling diolefin of four to five carbon atoms per molecule, produced by the dehydrogenation of a corresponding more saturated hydrocarbon, from accompanying dehydrogenation products, which comprises passing the effluent from such a dehydrogenation to a low point of an absorber, passing to a high point of said absorber a lean selective absorption liquid to effect a selective absorption of unsaturated hydrocarbons, removing unabsorbed gases from the system, passing a rich absorbent liquid stream from said absorbent step to a first stripper, effecting in said first stripper a partial stripping of said rich absorbent to remove therefrom a less unsaturated hydrocarbon material and returning at least a portion of the same to a low point of said absorber, passing the resultant partially stripped rich absorbent liquid to a second stripper, removing therefrom remaining absorbed material comprising predominantly diolefins, passing a resultant lean absorption liquid to a high point of said absorber, returning a portion of said separated absorbed diolefin material to a low point of said absorber, and removing from the process as a diolefin product a further portion of said material.

30 3. An improved process for the separation of a low-boiling diolefin of four to five carbon atoms per molecule, produced by the dehydrogenation of a corresponding more saturated hydrocarbon, from accompanying dehydrogenation products, which comprises passing the effluent from such a dehydrogenation to a low point of an absorber, passing to a high point of said absorber a lean selective absorption liquid to effect a selective absorption of unsaturated hydrocarbons, removing unabsorbed gases from the system, heating the rich absorption liquid at the bottom of said absorber to vaporize a portion of the material absorbed therein, passing from the bottom of said absorber a rich absorption liquid stream to a first stripper, effecting in said first stripper a partial stripping of said rich absorption liquid to remove therefrom less unsaturated hydrocarbon material and returning at least a portion of the same to the heated liquid in the bottom of said absorber, passing the resultant partially stripped rich absorption liquid to a second stripper, removing therefrom remaining absorbed material comprising predominantly diolefins, passing a resultant lean absorption liquid to a high point of said absorber, returning a portion of said separated diolefin material to the heated liquid in the bottom of said absorber, and removing from the process a further portion of said material as a diolefin product.

40 4. An improved process for the separation of pentadiene produced by the dehydrogenation of the corresponding C_5 hydrocarbons from accompanying dehydrogenation products, which comprises passing the effluent from such a dehydrogenation to a low point of an absorber, passing to

5 a high point of said absorber a lean selective absorption liquid to effect a selective absorption of unsaturated hydrocarbons, removing unabsorbed gases from the absorber, passing a rich absorbent liquid stream from said absorbent step to a first stripper, effecting in said first stripper a partial stripping of said rich absorbent to remove therefrom a less unsaturated hydrocarbon material and returning at least a portion of the same to a low point of said absorber, passing the resultant partially stripped rich absorbent liquid to a second stripper, removing therefrom remaining absorbed materials comprising predominantly pentadiene, passing a resultant lean absorption liquid to a high point of said absorber, returning a portion of said separated absorbed pentadiene material to a low point of said absorber, and removing from the process as a pentadiene product a further portion of said material.

6 5. An improved process for the separation of normal pentadiene produced by the dehydrogenation of normal C_5 hydrocarbons from accompanying dehydrogenation products, which comprises passing the effluent from such a dehydrogenation to a low point of an absorber, passing to a high point of said absorber a lean selective absorption liquid to effect a selective absorption of unsaturated hydrocarbons, removing unabsorbed gases from the absorber, passing a rich absorbent liquid stream from said absorbent step to a first stripper, effecting in said first stripper a partial stripping of said rich absorbent to remove therefrom a less unsaturated hydrocarbon material and returning at least a portion of the same to a low point of said absorber, passing the resultant partially stripped rich absorbent liquid to a second stripper, removing therefrom remaining absorbed material comprising predominantly normal pentadiene, passing a resultant lean absorption liquid to a high point of said absorber, returning a portion of said separated absorbed normal pentadiene material to a low point of said absorber, and removing from the process as a normal pentadiene product a further portion of said material.

70 6. An improved process for the separation of isoprene produced by the dehydrogenation of the corresponding more saturated C_5 hydrocarbons from accompanying dehydrogenation products, which comprises passing the effluent from such a dehydrogenation to a low point of an absorber, passing to a high point of said absorber a lean selective absorption liquid to effect a selective absorption of unsaturated hydrocarbons, removing unabsorbed gases from the absorber, passing a rich absorbent liquid stream from said absorbent step to a first stripper, effecting in said first stripper a partial stripping of said rich absorbent to remove therefrom a less unsaturated hydrocarbon material and returning at least a portion of the same to a low point of said absorber, passing the resultant partially stripped rich absorbent liquid to a second stripper, removing therefrom remaining absorbed material comprising predominantly isoprene, passing a resultant lean absorption liquid to a high point of said absorber, returning a portion of said separated absorbed isoprene material to a low point of said absorber, and removing from the process as an isoprene product a further portion of said material.
